J. Hutchison Jr.
Attorney.

UNITED STATES PATENT OFFICE

CARL STILL, OF RECKLINGHAUSEN, GERMANY

COKE OVEN AND DOOR THEREFOR

Application filed October 26, 1926, Serial No. 144,283, and in Germany March 22, 1926.

My invention relates to coke oven doors and its main object is the provision of means of an extreme simplicity and convenience for permitting the expansion of the coke oven 5 charge during operation.

Coke oven doors are known in which there is a certain amount of flexibility allowed for the expansion of the charge, for example by means of movable parts provided on the 10 inner side of the door, or by the provision of means for displacing the whole door itself in the direction of the axis of the oven. These known devices have the drawbacks that they are either too expensive and complicated or they impair and render difficult 15 the sealing of the door.

In the coke oven door according to the invention flexibility permitting the expansion of the coal charge is obtained in the simplest 20 and most effective manner by providing the inner lining of the door with recesses or cavities of such form and disposition that as the coal expands it is pressed into the recesses.

25 The accompanying drawing represents an example of a coke oven door according to the invention in vertical central section through the door and the adjoining portion of the oven chamber.

30 The oven chamber *k* is closed by a door *t* which is rigidly fastened in the usual manner by locking bars *d* supported in the buckstays *i* of the ovens, and by wedges *h* engaging with the former. The door *t* has a

35 lining formed substantially by firebricks *r* and *s*. The bricks *r* are shorter than the bricks *s*, so that recesses or cavities are formed between the projecting ends of the bricks *s*. In the example illustrated these recesses extend in the horizontal direction over 40 the whole width of the door *t*, but intermediate bricks *r* of the same length as the length of the bricks *s* may be arranged at intervals in order to strengthen the brickwork

45 and the durability of the lining. The coal *f* slips when the oven is charged for a certain distance into the recesses of the lining in the form of inclined protrusions *b*, but behind these there are still free spaces *c*. If 50 the coal charge *f* during the progress of cok-

ing tends to expand in consequence of its swelling properties, the coal is pressed into the empty spaces *c*, the protruding portions *b* being continually displaced outwards until the spaces *c* are entirely filled. The recesses or empty spaces *c* must be of such 55 form and disposition that the charge can be easily pressed into them. For this purpose it is necessary that the recesses should take up the largest possible portion of the 60 whole inner surface of the lining and should not be too narrow. When these conditions are fulfilled, a very effective flexibility is obtained by the simplest means permitting the 65 expansion of the coal charge, and the inconvenient and dangerous consequences of the expansion due to the swelling of the coal to be coked during the working, which often result in important damage to the whole 70 battery of ovens, are successfully avoided.

What I claim is:

1. A coke oven door comprising a metallic shell and alternate rows of short and long firebricks carried by the shell and forming a firebrick lining having recesses to receive 75 the expanding coal charge.

2. A coke oven door comprising a hollow metallic shell and alternate rows of short and long firebricks fitted in the shell, the short firebricks being flush with the inner 80 edges of the shell and the long firebricks projecting beyond the same to produce recesses for the reception of the expanding coal charge.

3. A coke oven adapted to receive a coal 85 charge therein and having a wall provided with a doorway, a door for closing said doorway, a firebrick lining in said door the adjacent firebricks of which extend inwardly to different extents, thereby providing recesses or cavities into which the coal charge 90 can enter when expanding.

4. A coke oven adapted to receive a coal charge therein and having a wall provided with a doorway, a door for closing said doorway, a firebrick lining carried by said door, alternate rows of firebricks extending inwardly to different extents, the longer of said firebricks being tapered so as to be thinner 95 at their projecting free ends.

5. A coke oven door having rigidly attached means providing recesses to permit the expansion of the adjacent coal charge, the total surface area of the recesses covering a greater portion of the exposed face of the door than the remaining unrecessed portions.
6. A coke oven door having fire brick means exposed to the adjacent coal charge and arranged to provide recesses for the reception of the expanding coal, said recesses being larger at their entrance than at their base.
7. A coke oven adapted to receive a coal charge therein and having a wall provided with a doorway, a door for sealing said doorway having an inner surface provided with projections and recesses, the tops of the recesses forming an angle with the horizontal line more acute than the slope inclination of the coal charge in the recesses and the total surface area of the recesses being greater than the remaining unrecessed portion of the inner surface of the door.
8. A coke oven door having recesses exposed to the coal charge within the oven, the total surface area of the recesses covering a greater portion of the exposed face of the door than the remaining unrecessed portion.

In testimony whereof I affix my signature.
